UNITED STATES PATENT OFFICE.

HAROLD GOOCH KERLOGUE, OF LONDON, ENGLAND.

BAG OR CARRIER FOR GOLF CLUBS AND THE LIKE.

Application filed December 19, 1921. Serial No. 523,522.

To all whom it may concern:

Be it known that I, HAROLD GOOCH KERLOGUE, a subject of the King of Great Britain and Ireland, residing at 36 Withering-
ton Road, Highbury, London, England, have invented a new and useful Improvement in and Relating to Bags or Carriers for Golf Clubs and the like, of which the following is a specification.

- 10 This invention relates to bags or carriers for golf clubs and the like and has for its primary object making it possible to readily and efficiently support the bag or carrier, when not being carried in the hand, in such
15 an upright position on the ground as to enable the clubs to be readily removed or replaced so enabling a player, without inconvenience, to dispense with the services of a caddie.
20 The present invention comprises essentially a fitting permanently attached to the mouth or upper portion of the usual bag or carrier but preferably removably attached thereto and so arranged as to be capable of
25 being readily fitted to any existing bag or carrier, and a pair of legs or struts so hinged or connected to said fitting as to be readily splayed or extended at their lower ends so as to form the two legs of a tripod, the third
30 support being formed by the bag, which is kept distended by one or more clubs within it.

In the accompanying drawing which illustrates this invention:—

- 35 Fig. 1 is a view in front elevation of the device for removable attachment to a golf bag or carrier.

Fig. 2 is a view in plan thereof, and

Fig. 3 is a longitudinal section on line

- 40 A—A of Fig. 2.

Throughout the views similar parts are marked with like letters of reference.

A tubular piece or socket a is provided with a sliding piece or plunger b adapted to move axially within it. The socket a also carries a compression spring c acting between the lower end of the plunger b and a plate or plug a^1 closing the lower end of the socket. The upper end of the socket a may be closed by a cap a^* . On the side of the sliding piece or plunger b is fixed or screwed thereto a pair of radially arranged transverse pins or studs b^1 each of which extends through a longitudinal slot a^2 formed 50 in the wall of the socket a . The outer end of each of these pins or studs is slotted to

receive a lug or plate d carried on the top of a socket d^1 and is hinged or pivoted to said pin or stud by a transverse pin d^2 . These sockets d^1 are each fitted with a leg or support d^3 , preferably of wood and of a total length less than the length of the bag or carrier to which the device is to be fixed. Below and in a line with these pins or studs b^1 are lugs a^3 carried on the plate a^1 , to 65 these lugs are pivoted or hinged at a^4 links e , which at their upper and opposite ends are hinged or pivoted at e^1 to the sockets d^1 . These links pass freely through slots in said sockets d^1 and in the slots a^2 in the socket a . 70

On the back wall of the socket a is fixed a spring clip f adapted to fit over and grip the mouth—or stiffening ring therein—and the side wall of the bag to which the device is to be applied. 75

When the device is applied to a bag or carrier the legs d^3 normally lie parallel with and flat against the wall thereof and when required to support the bag on the ground the legs are opened or splayed against the 80 action of the spring c (as shown in dotted lines on Fig. 3) so that they together with the bag—kept distended by one or more clubs within it—form a tripod with approximately equally spaced points of support 85 upon the ground.

With the legs extended the bag will be efficiently supported in such an upright position as to make it convenient to insert within it or withdraw from it, a club, and on lifting up the bag, the legs will automatically—due to the spring—close in and rest against the outer surface of the bag. Instead of forming the socket a and plunger b circular in cross section as shown on the drawing, it 95 may be made of triangular or other suitable shape in cross section. In some cases the cap a^* may be omitted and the plunger b be extended upwardly to project from the socket a and furnished with a knob which 100 when depressed will open or splay the legs d^3 .

I declare that what I claim and desire to secure by Letters Patent is:—

1. A fitting for bags or carriers for golf clubs comprising a tubular piece; a plunger 105 working within said tubular piece, a spring acting in compression between the lower end of the plunger and the closed end of the tubular piece, a pair of studs fixed to the plunger and extending through a pair of 110 slots formed in the wall of the tubular piece, a pair of sockets pivoted to said studs and

each carrying a leg, a link pivoted to each leg socket below its pivoting point and hinged at its opposite end to the tubular piece and contained within slots therein and 5 the tubular piece, and means for attaching the tubular piece to the mouth of a golf club bag or carrier, as set forth.

2. A fitting for bags or carriers for golf clubs comprising a tubular piece, end covers 10 therefor, a plunger sliding axially within said piece, a compression spring acting between the lower end cover and the lower end of the plunger, a pair of slotted studs fixed radially to the plunger, a pair of slots in the

side wall of the tubular piece and through 15 which the studs project, a pair of sockets pivoted at their upper ends to the slotted ends of the studs, a pair of legs fitted within said sockets, a link pivoted to each socket below its pivoting point and pivoted at its 20 opposite end to the lower end cover of the tubular piece, slots within the sockets and tubular piece to receive the links and a spring clip fixed exteriorly to the back wall of the tubular piece shaped to fit over and 25 grip the mouth of the golf club bag or carrier, as set forth.

HAROLD GOOCH KERLOGUE.
